ABRADING DEVICE

Hector E. Goldie, Montreal, Quebec, Canada, assignor to Rubenstein Bros. Company, Montreal, Quebec, Canada, a corporation of Quebec

Application April 5, 1946, Serial No. 659,778
In Canada January 23, 1946

7 Claims. (Cl. 51—249)

1

This invention relates to a cloth cutting machine, and more particularly to an abrading device attached to or forming part of a reciprocating straight knife cloth cutting machine.

Having regard to the foregoing, it is a principal object of this invention to provide a sharpening device adapted to form a part of the cloth cutting machine, which is fully automatic in operation, light in weight, and compact in structure.

It is a further object of this invention to provide an abrading device which reciprocates the abrading wheels at a governed speed, and automatically frees the abrading wheels from the knife at the end of one down and up cycle.

It is a further object of this invention to provide an abrading device which after one abrading cycle automatically stops leaving the cutter knife free so that the operator may continue cutting without further adjustment.

It is a further object of this invention to provide means for guiding the abrading wheels in their reciprocal cycle in line with the knife edge.

Statement of invention

The applicant's invention is applied to a cloth cutting machine of the reciprocal straight knife type having a motor adapted to drive the knife. In accordance with the invention, this apparatus is provided with a rod having a helically double threaded keyway in its peripheral surface and adapted for rotation and reciprocation parallel to the knife, the rod being rotated from the motor which drives the knife, a follower adapted to engage the thread on the rod to cause its reciprocation upon its rotation. A sharpening carriage is mounted on the rod for reciprocation with it and abrading wheels are rotatably mounted on the carriage and driven by rotation of the rod. With respect to the rotation of the rod in a sharpening cycle, a driven element is connected to the rod for rotating it, a driving element connected to the motor, the driven element and the driving element associated mechanism constituting a clutch adapted to be engaged to rotate the rod and disengaged at the end of the sharpening stroke.

In accordance with a more specific phase of the invention, it also includes means for guiding the abrasive wheels relatively parallel to the knife, said means including guide members adapted to straddle the knife guide, and resiliently ride on each side thereof to guide the abrasive wheels in a path parallel with the guide which guides the path of the knife.

Detailed description

Still other features will be apparent in the

course of the following detailed description in which reference is made to the accompanying drawings, wherein:

Figure 1 is a cutaway front view of a preferred form of the abrading mechanism as adapted to a cloth cutting machine of the vertical reciprocating straight knife type.

Figure 2 is a cutaway side view of the abrader mechanism in Figure 1.

Figure 3 is a rear elevation of the inside of the main housing of the abrader showing the starting and stopping mechanism removed from the cutting machine with the upper portion of the housing, the rod and the abrading carriage not shown.

Figure 4 is a plan view of the housing shown in Figure 3.

Figure 5 is an elevation of the starting assembly swivel member removed from the remainder of the apparatus.

Figure 6 is a plan view of the starting assembly swivel member removed from the remainder of the apparatus.

Figure 7 is a schematic view of the abrader carriage showing the gear train mounted on the abrading arms.

Figure 8 is a plan view of the abrader carriage showing in addition the knife, the guideway and the abrader carriage guide bracket acting on the knife guideway.

Figure 9 is a side elevation of the abrader carriage, the casing cut away to show the gear train from the reciprocating rod to the abrading wheels.

Figure 10 is a front elevation of the abrader carriage with the guide bracket cut away showing the inter-locking of the abrader wheel surfaces to allow even pressure on each side of the knife.

Figure 11 is a plan view showing the method of attaching the guide arm to the abrader carriage.

Figure 12 is a reverse plan view of the cover of the abrader carriage showing the main driving gear which is attached to the reciprocating rod.

Figure 13 is a plan view of the abrader arms showing the spring urging the abrasive wheels inwardly toward the knife edge.

Figure 14 is a reverse cutaway plan view of the gear chain shown in Figure 7.

Main assembly

The abrading or knife sharpening apparatus is mounted on a slightly modified straight knife cloth cutting machine consisting of a base plate 1, a cloth lifting plate 2, rollers 3, on which the cutter is moved about the cutting table, a standard or cutting knife guide 4, a motor 8 mounted on the cutting machine frame 5 and a guide handle 6. A straight, cloth cutting knife 9 is

reciprocated by a crank 10 suitably connected to the motor 8 the knife being guided by a grooved guideway in the standard 4.

A housing 11 is mounted on the cutting machine frame 5, and adapted to provide motion to the abrading apparatus is a transmission comprising a friction wheel 80 and worm 81, adapted to swivel and so engage the shaft of the cutting machine motor. A member 44 (Figures 6 and 7) mounted within the housing 11 provides the swivel mounting for the friction wheel. A gear 82 in meshed contact with the worm 81 is mounted on a sleeve 42 which is adapted to rotate within the member 44 a rod 40 slidably operable within the sleeve 42 is keyed to the sleeve 42 and receives rotary motion thereof. A traverse thread cut on the face of the rod 40 is engaged by a follower key 41 mounted in the housing 11 which upon rotation of the rod 40 forces the rod into a reciprocating down and up motion. A starting lever 58 attached to the member 44 by the collar 45 controls the swivel motion of the member 44.

The starting mechanism

The assembly comprising the friction wheel 80, the member 44 and the starter lever 58 as detailed are swivelly mounted whereby the forward and backward motion of the starting lever as shown in Figure 4, places the friction wheel in contact with the drive shaft of the motor and releases it, the dotted lines showing the disengaged position. An automatic stopping rod 70, which will be detailed later, contacts a collar 57 which is one end of a sleeve 55 slidably mounted on the starting lever 58, forcing the starting lever into the disengaged position. Pressure on the head 56 of the sleeve 55 forces the sleeve in, compressing a spring 59 and clears the collar 57 past the stopping rod 70, then allowing the starting lever 58 to move to the position B putting the friction wheel in contact with the drive shaft of the motor. A tension spring 60 tends to hold the member 44 in this position.

The abrading assembly

The abrading assembly consists of a main carriage 43 in which rotates the main driving gear 30 which is directly attached to and receives rotary motion from the main reciprocating rod 40. A pair of spring urged arms 21 and 22 are pivotally mounted to the main carriage 43 by the axles of the gears 32 A and B and each carry a train of gears 32, 33, 34, to rotate the abrading wheels which are mounted on these arms. The axle of the head gear 32A carries a gear 31 which is driven directly by the main driving gear 30. The two head gears 32 A and B, are in direct contact whereby rotating the abrading wheels 20, which are mounted on the axles of the gears 34 A and B, in opposite directions. A spring, 23 as shown in Figure 12, urges the free ends of the arms 21 and 22 towards each other, thereby causing the desired pressure to be exerted by the abrading wheels when in contact with the knife edge 9.

When the abrading assembly is put in motion by the rotating of the reciprocating rod, the whole assembly is reciprocated the full length of the cutting blade by means of the key 41 being engaged in the reciprocating thread out on the surface of the rod 40. To provide for the accurate guiding of the abrading wheels 20 in a line parallel with the knife a guide frame 90 is mounted on the abrader carriage (Figures 8, 9, 11). A guide roller 92 engages one side of the

standard 4 and a spring urged guide wheel 93 mounted on the bracket 90 engages a groove 94 on the other side of the standard 4, thus when the abrader carriage reciprocates in its sharpening cycle, the abrader wheels are carried in parallel line with the knife edge.

The automatic stopping rod

The automatic stopping rod 70 in this preferred structure consists of a round rod pointed at one end, flat on the other, and slidably mounted within the housing 11 whereby the pointed end may contact the collar 57 of the starting lever, and the flat end contact the abrader carriage 43 during the last stage of its upward motion. The rod 70 is urged downward by a spring 71 acting between the mounting and a stop collar 72 on the rod which is permitted to slide downwardly by the action of the springs 71, as the carriage 43 starts to descend in an abrading cycle, is clear from any contact with the starting sleeve collar 57. As the carriage in the last stages of this return motion contacts the lower end of the rod 70, the rod is forced upwardly against the downward urging of the spring 71 placing the pointed end of the rod in contact with the starting lever collar 57 causing the starting lever 58 to swivel to one side, thus swiveling the sleeve 44 and the component parts of the swivelly mounted transmission assembly including the friction wheel out of engagement with the cutting machine motor.

In order to provide clearance of the starting lever collar 57 from the rod to start the abrading cycle, the starting lever sleeve 55 is slidably mounted on the starting lever 58 and spring urged into a downward position aligning the collar 57 with the pointed end of the stop rod 70 by the spring 59 (as illustrated in Figure 1). Manual pressure on the end 56 of the starting sleeve places the collar 57 out of alignment with the end of the rod 70, thus allowing the starting lever to swivel a distance equal to the height of the collar above the sleeve 55 which is sufficient to place the friction wheel into engagement with the cutting machine motor, thus starting the abrading cycle and the outward motion of the carriage 43. As the rod 70 descends by the force of the spring 71 and the outward motion of the carriage 43, the sleeve 55 and the collar 57 are forced back in their normal or outward position by the action of the spring 59 aligning the collar 57 with the pointed end of the stop rod 70 which, when forced upward by the return motion of the carriage swivels the friction wheel out of contact with the cutting machine motor thereby stopping the abrading cycle.

The separating pin

The separator pin 50 is wedge shaped and is mounted on the bottom of the housing 11 in such a manner that upon the last stage of upward motion of the abrader carriage, the separator pin wedges between the two abrader bearing arms 21 and 22 at a point 51 (Fig. 8) thereby forcing the abrader arms apart thus freeing the abrader wheels from the knife edge at the uppermost stage of the abrader's reciprocal run.

The presser foot safety stop

The presser foot 7 in this preferred structure is slightly elongated and is mounted on the face of the housing 11 by the bracket 12 in which the presser foot rod 75 is slidably held. When the presser foot 7 is elevated the rod 75 extends above

the top of the bracket 12, but when fully extended as shown in Figure 2 the end of the rod 15 is below the top surface of the bracket 12.

Substantially centrally pivotally mounted to the upper face of the bracket 12 is an irregularly shaped member 76 adapted to engage the presser foot rod 75 if the rod is extending above the upper surface of the bracket 12, but to pivot freely if the presser foot rod 75 is fully extended so that the end of the rod 75 is below the upper surface. The opposite end of the member 76 is spring urged into contact with the side of the collar 57 of the starting rod, thereby making it impossible to press the starting sleeve 55 inwards if the presser foot rod 75 is extending above the upper face of the bracket 12, whereby it is engaged by the member 76 holding it rigid against pivotal movement, thus preventing the inward movement of the sleeve 55 which is necessary in order to swivel the member 44 to engage the friction wheel 80 with the cutting machine motor to start the sharpening cycle of the abrader.

The knife sharpening elements in this preferred structure consists of a pair of abrader wheels, each having a plurality of spaced-apart blade engaging surfaces, for engaging the opposite sides of the cutting knife at alternate points as illustrated in Figures 1, 9 and 10, made of emery or other suitable abrasive material. The abrasive wheels being mounted on the axle of the gears 34A and B respectively.

The sharpening operation

Assuming the abrader mechanism to be in its rest or stopped position, wherein the friction clutch wheel is disengaged from the drive shaft of the motor, the starter rod is in its rearward position A (Figure 4) with the sleeve in the out position. The abrading assembly is in its top or rest position, as in Figure 1, the carriage having forced the automatic stopping rod up and into contact with the collar of the starting lever sleeve, holding the starting lever in its off position B (Figure 4). The abrading wheels are free from the knife edge due to the arms being wedged apart by the action of the separator pin. The presser foot is fully extended and the cutting machine is ready for cutting or sharpening.

No adjustments are necessary to sharpen the cutting knife, merely press in on the starting lever sleeve and the action of sharpening and stopping is completely automatic.

To sharpen the knife, the operator presses lightly on the starting lever sleeve 56, thus freeing the collar 57 from contact with the automatic stop rod allowing the spring 60 to swivel the start-stop rod assembly to the B position, putting the friction clutch wheel into contact with the main shaft of the running cutter motor. The rotary motion thus imparted to the friction wheel is carried through the worm 81, the gear 82, the sleeve 42 to the reciprocating rod 40 which is keyed to the sleeve 42. The stationary guide key 41 being engaged in the reciprocating thread cut in the periphery of the rod 40 forces this rod, when it rotates, into a reciprocating down and up motion equal to the length of the thread, which is designed the same length as the cutting edge of the knife.

The rotating motion of the rod 40 is carried through the gear train from gear 30 directly connected to the rod 40 through gear 31 to 32 A and B on to 34 A and B (see Figure 7). The abrading stones mounted on the axles of the gears 34 A and B are thus rotated in opposite directions and re-

ciprocated the length of the blade as explained above.

As the rod 40 starts to rotate and reciprocate several actions take place at the same time, as follows:

(a) The main abrader carriage, which is mounted by gear 30 to the rod 40, starts its downward travel, thereby freeing the abrader arms from the wedge shaped separator pin, allowing the spring 23 to force the abrader wheels against opposite sides of the knife edge as the carriage reciprocates.

(b) As the carriage 43 starts downward it releases contact with the automatic stopping rod 10 which is forced downward by spring 11 to the extent of the collar 72 thus freeing the upper end of the rod 70 from the side of the collar 57 of the starting lever sleeve, the spring 58 then pushing the sleeve 55 to its out or extended position as shown in Figure 4, position B.

The abrading assembly makes a full downward and upward knife sharpening cycle. As it nears the last stage of its upward motion the two arms 21 and 22 are engaged by the separating pin 50 which forces them apart thus freeing the abrader wheels from the knife edge. At the same time the carriage also contacts the automatic stopping rod forcing it upward and into contact with the starter assembly sleeve collar 57, the action of contact being to force the starting lever rearward from position B to A (Fig. 4) thus swivelling the member 44 and disengaging the friction wheel from the motor shaft, thus bringing the whole abrading apparatus to a stop with the carriage up and the abrader wheels disengaged or free from the cutting knife.

In the event of the presser foot not being fully extended, it would be impossible to start the abrading mechanism due to the lever 76 being rigidly held against the spring side of the collar 57 thus preventing the "in" motion of the sleeve necessary to free the collar 57 from the stopping rod 10 for starting.

It will be understood that without departing from the spirit of the invention or the scope of the claims, various modifications may be made in the specific expedients disclosed. The latter are illustrative only and not restrictive, it being desired that only such limitations shall be placed thereon as may be required by the state of the prior art.

I claim:

1. An apparatus of the type described, comprising, a single motor, a straight knife reciprocable by said motor, a rod having a helically double-threaded keyway in its peripheral surface adapted for rotation and reciprocation parallel to the knife, a follower adapted to engage the thread on said rod for causing reciprocation of said rod on its rotation, a carriage mounted on the rod, rotatable abrading means mounted on said carriage and rotatable by said rod, a driven element connected to said rod for rotating it, a driving element connected to said motor, a clutch between said driven element and said driving element, said rod being positively driven from the motor when the clutch is engaged thereby to cause outward and return sharpening movements of the abrading means in a sharpening cycle and rotating sharpening movements of the abrading means, manual means for causing engagement of said clutch, and means operated by contact with said carriage in its return movement for causing disengagement of said clutch.

2. An apparatus, according to claim 1, including

a pair of arms mounted on said carriage, said abrading means including wheels mounted on respective arms adapted for movement towards and from said knife, means for acting on said arms to urge said wheels into contact with said knife, and means adapted to contact said arms on their return movement towards the end of the sharpening stroke to spread said arms, thereby separating the wheels from the knife.

3. An apparatus of the type described, comprising, a motor; a straight knife adapted for reciprocation, drive means from said motor to said knife; a housing, a transmission assembly in the housing comprising a swivel mounting swivelly mounted on said housing, a sleeve mounted for rotation within said swivel mounting, a gear fixedly mounted on said sleeve with said sleeve as an axle, a worm mounted on said swivel mounting adapted to mesh with said gear, a rotatable clutching element axially fixed to said worm, the swivel action of said swivel mounting adapted to move said clutching element into and out of engaging contact with said motor to rotate said sleeve, means for swivelling said swivel mounting, a rod having a helically double-threaded keyway in its peripheral surface mounted for reciprocation within said sleeve and keyed to said sleeve for rotation therewith, a follower adapted to engage in said double-threaded keyway to reciprocate said rod upon rotation in an outward and return motion parallel to said knife, a carriage mounted on said rod, abrading wheels mounted on said carriage, means adapted to urge said abrading wheels into contact with said knife, and means adapted to disengage said wheels from said knife at the end of each return stroke of the carriage.

4. An apparatus of the type described, comprising, a motor, a straight knife adapted for reciprocation, drive means from said motor to said knife, a housing, a swivel mounting in said housing, a friction wheel rotatably mounted on said swivel mounting, the swivel action of said swivel mounting adapted to move said friction wheel into and out of friction contact with said motor, a rod mounted within said swivel mounting, transmission means between said friction wheel and said rod adapted to rotate and reciprocate said rod, a carriage mounted on said rod, abrading means rotatably mounted on said carriage adapted to straddle said knife, a first spring acting between said swivel mounting and said housing to normally urge said friction wheel into engagement with said motor, a lever attached to said swivel mounting, a sleeve slidably mounted on said lever, a collar on said sleeve, a second spring adapted to urge said sleeve in an outward direction on said lever, a stop rod slidably mounted in said housing actuated by contact with the carriage on its return movement to contact said collar and move said lever to swivel said friction wheel out of contact with said motor.

5. An apparatus, as set forth in claim 4, in which the sleeve slidably mounted on said lever is adapted to be manually urged in an inward direction against said second spring to disengage said collar from said stop rod, whereby said friction wheel is engaged with said motor by the action of said first spring.

6. A straight knife cutting machine, comprising in combination, a reciprocating knife, a knife 10 guide, a motor for driving the said knife, abrasive wheels mounted on a carriage for downward and upward linear movement in a sharpening cycle, mechanism adapted to be disengageably engaged with the motor for causing both a linear down and up movement of the wheels parallel to the knife edge and rotating the abrasive wheels, means for guiding said abrasive wheels relatively parallel to said knife, said means comprising a bracket, a pair of oppositely disposed guide members 15 rotatably mounted on said bracket, at least one of said guide members being resiliently mounted, said guide members adapted to straddle the knife guide and ride on each side thereof to guide said abrading wheels parallel with said knife.

7. An apparatus of the type described, comprising, a single motor, a straight knife adapted for reciprocation, drive means from said motor to said knife, a housing, a rod having a helically 30 double-threaded keyway in its peripheral surface adapted for rotation and reciprocation parallel to the knife, and a follower acting in said keyway to cause reciprocation of said rod upon rotation, a driven element connected to said rod for rotating it, a driving element connected to said motor, a clutch between said driven element and said driving element, a carriage mounted on said rod, a pair of arms mounted on said carriage, abrading wheels rotatably mounted on each of said arms, 35 means for acting on said arms to urge said abrading wheels into contact with said knife, means adapted to contact said arms on their return movement to spread said arms to disengage said wheels from said knife.
